(57) **CLAIM**

I claim the ornamental design for a corner protector, as shown and described.

DESCRIPTION

FIG. 1 is a perspective view of a corner protector, showing my design;

FIG. 2 is a top view of the corner protector of FIG. 1;

FIG. 3 is a bottom view of the corner protector of FIG. 1;

FIG. 4 is a front elevation view of the corner protector of FIG. 1;

FIG. 5 is a rear elevation view of the corner protector of FIG. 1;

FIG. 6 is a left elevation view of the corner protector of FIG. 1;

FIG. 7 is a right elevation view of the corner protector of FIG. 1;

FIG. 8 is a perspective view of a second embodiment of a corner protector, showing my design;

FIG. 9 is a top view of the corner protector of FIG. 8;

FIG. 10 is a bottom view of the corner protector of FIG. 8;

FIG. 11 is a front elevation view of the corner protector of FIG. 8;

FIG. 12 is a rear elevation view of the corner protector of FIG. 8;

FIG. 13 is a left elevation view of the corner protector of FIG. 8; and,

FIG. 14 is a right elevation view of the corner protector of FIG. 8.
